UNITED STATES PATENT OFFICE

RALPH W. DOWNES, OF KANSAS CITY, MISSOURI, ASSIGNOR TO POTTER MANUFACTURING CORPORATION, OF CHICAGO, ILLINOIS, A CORPORATION OF DELAWARE

RELEASE DEVICE FOR FIRE ESCAPE DOORS

Application filed February 16, 1931. Serial No. 515,973.

This invention relates to improvements in a release device for fire escape doors and refers more particularly to a spring plate positioned beneath the doors having a locking member adapted to engage the doors which are equipped with spring hinges, which member holds the doors in a closed position and releases them when the spring plate is depressed.

10 A further feature of the invention is the replacement of the horizontal bar across the door opening by two corner bars or hand grips positioned in the corners of the door opening to facilitate a person's entering the 15 fire escape.

The invention is applicable particularly to an entrance opening to tubular fire escapes used in connection with public buildings such as schools and like institutions.

20 Fig. 1 is a front elevational view of a fire escape opening with the doors in a closed position.

Fig. 2 is the same view with the doors in an open position.

25 Fig. 3 is an enlarged perspective view with parts broken away showing more clearly the operation of the device.

Referring to the drawings, in the entrance to the tubular fire escape are swung, by means 30 of spring hinges 1, doors 2 and 3. Handles 4 are mounted on the doors to facilitate closing them after they have been swung open. In the floor 5 in front of the opening is a floor plate 6, preferably of steel or some non-corrosive metal such as brass or nickelized iron or 35 steel. Screwed or otherwise fastened to the front of the floor plate 6 is a spring plate 7. To enclose the open ends are guard plates 8 which are fastened to the floor and overlap 40 the spring plate as shown at 8A. At the free end of the spring plate is a bar lock 9 rigidly attached to the spring plate and positioned directly beneath the bottom of the doors 2 and 3. In the bottom edge of the door 45 is rabbed out, a groove or channel 10, which fits over the bar 9 when the doors are in a closed position. The engagement of the grooves in the doors with the bar 9 holds the spring hinged doors in a closed position.

50 Along the lower edge in front of each door

is a metal panel 11, which is rounded off at 11A so that when the doors are closed, this rounded off portion contacts the top of the bar 9 near its ends. The contact of the bar 9 by both doors as they are being closed 55 depresses the spring plate 7 automatically bringing the bar into engagement with the slots 10 in the doors when they are completely shut. In this position, the bar 9 snaps into the grooves 10 and maintains the doors in a 60 closed position until the spring plate is again depressed sufficiently to release the doors and permit them to spring open. To facilitate the operation, the front edge of the bar is 65 rounded off as shown in Fig. 3.

In addition to the functioning as a spring release, the horizontal cross bar usually used near the tops of the doors for swinging persons into the tubular fire escape has been replaced by curved bars positioned in the corners of the opening adapted to be gripped by a hand on either side of the opening when a person is swinging himself into the tubular 70 fire escape.

Further obvious advantages of the releasing treadle or threshold plate are that it is unnecessary for the occupants to stoop to release the lugs on the doors; wind cannot blow the doors back in the way of the occupants due to the spring hinges holding the 80 doors open; furthermore the lug on the threshold plate which fits into the rabbeted groove on the doors, being rounded, permits the doors to open when pressure is applied to the doors as well as the threshold plate. 85 Single bars arranged in the corners in place of a horizontal bar across the center of the opening, permit small as well as large people to enter the tube without difficulty. The 90 kick plates on the doors, being rounded at the ends, permit the doors to be pulled shut without forcing down the threshold plate. These advantages are inherently associated with the mechanism for operating the doors and, although each in itself seems to be of 95 little importance, the combination functions positively and with the least possible effort in the opening of the doors and in closing the doors.

I claim as my invention:

1. A release device for a spring hinged fire escape door comprising a spring floor plate having a raised bar transversely positioned adjacent its free end, a groove in the door adapted to engage the bar and to cooperate therewith to hold the door in a closed position, the depression of the spring plate adapted to release the bar from the groove in the door.
2. In a release device for spring hinged fire escape doors, a combination with a spring floor plate having a free end beneath the doors, a bar latch mounted upon the free end of the spring plate, a groove in the bottom of the doors for engaging the bar latch, said engagement accomplished when the doors are in a closed position and disengagement effected with the depression of the spring plate.
3. In an automatic fire escape door releasing device including in combination a fire escape door and groove in the bottom of said door, an inherently resilient floor plate, a latching bar secured to said floor plate for coaction with said groove to hold the door in its locked position whereby when pressure is brought to bear on said inherently resilient floor plate, it will be depressed to permit said locking bar to move to unlocking position.
4. In an automatic fire escape door releasing device including in combination a fire escape door, latching means on said door and an inherently resilient floor plate, means on said floor plate adapted to coact with the latching means on said door to hold the door in closed position whereby when pressure is brought to bear on said floor plate, it will be depressed to permit unlatching of said door.
5. In an automatic fire escape door releasing device including in combination a fire escape door, a groove in the bottom of said door, a movable floor plate, a latching bar secured to said floor plate for coaction with said groove to hold the door in its locked position whereby when pressure is brought to bear on said floor plate, it will be depressed to permit said locking bar to move to unlocking position.

In testimony whereof I affix my signature.

50 RALPH W. DOWNES.
